UNITED STATES PATENT OFFICE.

AIME BOULANGER, OF NORMANDIN, QUEBEC, CANADA.

HOISTING DEVICE.

Application filed January 20, 1923. Serial No. 613,972.

To all whom it may concern:

Be it known that I, AIME BOULANGER, a subject of the King of Great Britain, residing at Normandin, Province of Quebec, Canada, have invented certain new and useful Improvements in Hoisting Devices; and I do hereby declare that the following is a full, clear, and exact description of the invention, such as will enable others skilled in the art to which it appertains to make and use the same.

The present invention pertains to novel improvements in a hoisting device designed particularly for use on farms.

The primary object of the invention is the provision of a device of this character including a winding drum, the direction of rotation of which may be reversed at will. Obviously, the drum is turned in the winding direction to raise the load, and in the opposite direction to allow the descent of the free unweighted end of the cable after the load has been removed therefrom.

The invention further includes a braking mechanism for preventing rotation of the drum in case the engine should stop at an undesired time. Because of the fact that gas engines which are used on farming implements are likely to stop at an unexpected moment, this braking device is useful in preventing the descent of a partly raised load in the event that the engine should stop unexpectedly.

The invention is fully disclosed in the following description and in the accompanying drawings in which:

Figure 1 is a side elevation of the device;

Figure 2 is a plan view;

Figure 3 is an end view;

Figure 4 is a fragmentary side elevation opposite to Figure 1;

Figure 5 is a fragmentary side elevation corresponding to Figure 1, showing the auxiliary pulley in contact with one of the fly wheels;

Figure 6 is a section on the line 6-6 of Figure 4; and,

Figure 7 is a section on the line 7-7 of Figure 6.

The device comprises a base 1 on which is mounted a gasoline engine 2 including a cylinder 3. The engine casing includes a pair of vertical members 4 the tops of which are fitted with bearings 5 for supporting in a rotatable manner the crank shaft 6. The

latter is connected to the piston (not shown) of the engine by means of a connecting rod 7 in the usual manner.

On the ends of the crank shaft are mounted fly wheels 8 and 9, the end adjacent the wheel 8 having an extension 10 through which is passed a pin 11. On this end is slidably received a driving pulley 12 on the inner face of which is formed a boss 13 having a transverse slot 14 adapted to receive the pin 11. A stem 15 extends from the outer face of the pulley and has formed thereon a pair of spaced collars 16. A bracket 17 is secured to the base in a line beneath the extension 10 and stem 15, and has pivoted thereto a shifting lever 18 which straddles the stem between the collars 16 in such a manner that the pulley 12 can be moved upon actuation of the lever.

On the base 1, forward of the side members 4 are mounted a pair of blocks 19 and 20, one end of a counter shaft 21 being journaled in the block 19. A bearing block 22 having elongated vertical slots 23 formed therethrough is slidably mounted on the block 20 by means of bolts 24 passing through the slots and extending into the block. The other end of the counter shaft 21 is journaled in the slideable block 22. On one end of the counter shaft is keyed a driven pulley 25 in alignment with the driver 12, a belt 26 being used for transmitting power from the driving to the driven pulley. At the opposite end of the counter shaft is mounted an auxiliary pulley 27 in alignment with the fly wheel 9. A lever 28 has its intermediate portion connected to the counter shaft 21, as shown in Figure 1, the lower end being pivoted to the base 1, as indicated by the numeral 29. Intermediate the pulleys 25 and 27, a drum 30 is fixed to the counter shaft, having a hoisting cable 31 wound therearound.

In operation, the auxiliary pulley 27 is normally held out of engagement with the fly wheel 9, as shown in Figures 1 and 2. The pulley 12 is shifted inwardly so that the pin 11 is received in the slot 14, whereby the pulley 12 is rotated with the crank shaft and transmits power to the driven pulley 25 and through the belt 26. The crank shaft turning in a clockwise direction consequently causes the drum to rotate in the same direction whereby the cable 31 is wound thereon. In this position the device can ob-

viously be used for hoisting the cable being merely trained over a pulley fixed to an elevated support.

At the end of a hoisting operation, after 5 the load has been removed from the end of the cable, the weight of the latter even when combined with the grapple is insufficient to lower the same. Accordingly, the shifting device 18 is pulled outwardly so that the 10 pulley 12 is freed from the pin 11 and no power is transmitted therefrom to the drum. The lever 28 is now pushed rearwardly, bringing the auxiliary pulley 27 into engagement with the fly wheel 9 whereby the drum 15 is rotated in a counter clockwise direction allowing the free end of the cable to descend.

To the inner face of the block 20 is pivoted a brake lever 33 adapted for engagement with the auxiliary pulley 27. Inasmuch as this device is adapted for use on farms where gas engines are generally employed, it is very likely that the engine will stop in the midst of a hoisting operation. In the event that such an occurrence takes 25 place, the descent of the suspended load is avoided by upward pull on the lever 33, as a consequence of which the auxiliary pulley 27 is brought into close engagement with the fly wheel 9 and is braked, thus stopping 30 rotation of the drum 30. Furthermore, when the device is used to lower a load from an elevated position without the operation of the engine, the brake lever may be employed in the above described manner to prevent a 35 too rapid descent.

While a specific embodiment of the invention has been illustrated and described, it is to be understood that various alterations in the details of construction may be made 40 without departing from the spirit of the invention as indicated by the appended claims.

Having thus fully described the invention, what I claim as new and desire to protect by Letters Patent is:—

45 1. A hoisting device comprising a crank shaft, a fly wheel at each end thereof, one of said ends being extended, a driving pulley slidably mounted on said end and having a clutch engagement therewith, a counter shaft 50 operatively connected with said driving pulley, a drum mounted on said shaft, an auxiliary pulley mounted on said shaft in alignment with one of said fly wheels and adapted 55 for engagement therewith.

60 2. A hoisting device comprising a crank shaft, a fly wheel at each end thereof, one of said ends being extended, a driving pulley slidably mounted on said end and having a clutch engagement therewith, a counter shaft journalled in parallel relation with said crank shaft and having one end slidably mounted with relation thereto, an operative connection between said driving pulley and said counter shaft, a drum mounted 65 on the counter shaft, an auxiliary pulley

mounted on the counter shaft in alignment with one of said fly wheels, and means for shifting the slidable end of the counter shaft.

3. A hoisting device comprising a crank shaft, a pin passed through one end thereof, 70 a driving pulley slidably mounted on said end, a boss formed on one face of said pulley and having a slot cut therein adapted to receive said pin, a fly wheel keyed to the crank shaft, a counter shaft mounted in parallel relation with said crank shaft and having one end slidable with relation thereto, an operative connection between the driving pulley and the counter shaft, a drum mounted 75 on the counter shaft, an auxiliary pulley keyed to the counter shaft in alignment with the fly wheel, and means for shifting said slidable end to bring the auxiliary pulley 80 into and out of engagement with the fly wheel.

4. A hoisting device comprising a crank shaft, a pin passed through one end thereof, 85 a driving pulley slidably mounted on said end, a boss formed on one face of said pulley and having a slot cut therein adapted to 90 receive said pin, a fly wheel keyed to the crank shaft, a counter shaft mounted in parallel relation with said crank shaft and having one end slidable with relation thereto, an operative connection between the driving 95 pulley and the counter shaft, a drum mounted on the counter shaft, an auxiliary pulley keyed to the counter shaft in alignment with the fly wheel, and means for shifting said 100 slidable end to bring the auxiliary pulley into and out of engagement with the fly wheel.

5. A hoisting device comprising a crank shaft, a pin passed through one end thereof, 105 a driving pulley slidably mounted on said end, a boss formed on one face of said pulley and having a slot cut therein adapted to receive said pin, a fly wheel keyed to the crank shaft, a counter shaft mounted in parallel relation with said crank shaft and having one end slidable with relation thereto, an operative connection between the driving 110 pulley and the counter shaft, a drum mounted on the counter shaft, an auxiliary pulley keyed to the counter shaft in alignment with the fly wheel, means for shifting said 115 slidable end to bring the auxiliary pulley into and out of engagement with the fly wheel, and a lever pivoted to the base of the machine adjacent the auxiliary pulley and 120 adapted to engage the same.

6. A hoisting device comprising a frame, a crank shaft journalled therein, means for driving said crank shaft, a driving pulley 125 slidably mounted on one end of said shaft and having a clutch connection therewith, means for shifting said pulley, a fly wheel mounted on the opposite end of said shaft, a counter shaft journalled in the frame in 130 parallel relation with the crank shaft and

having one end slidably supported with relation thereto, an operative connection between the driving pulley and the counter shaft, a drum mounted on the counter shaft, 5 an auxiliary pulley keyed to the counter shaft at the slidable end and in alignment with the fly wheel, and means for shifting said slidable end to bring the auxiliary pulley into and out of engagement with the fly wheel.

7. A hoisting device comprising a frame, a crank shaft journalled therein, means for driving said crank shaft, a driving pulley slidably mounted on one end of said shaft 15 and having a clutch connection therewith, means for shifting said pulley, a fly wheel mounted on the opposite end of said shaft, a counter shaft journalled in the frame in parallel relation with the crank shaft and having one end slidably supported with relation thereto, an operative connection between the driving pulley and the counter shaft, a drum mounted on the counter shaft, 20 an auxiliary pulley keyed to the counter shaft at the slidable end and in alignment with the fly wheel, means for shifting said slidable end to bring the auxiliary pulley into and out of engagement with the fly wheel, and means for shifting said 25 slidable end to bring the auxiliary pulley into and out of engagement with the fly wheel.

ley into and out of engagement with the fly wheel.

8. A hoisting device comprising a frame, 30 a crank shaft journalled therein, means for driving said crank shaft, a driving pulley slidably mounted on one end of said shaft and having a clutch connection therewith, means for shifting said pulley, a fly wheel mounted on the opposite end of said shaft, a counter shaft journalled in the frame in parallel relation with the crank shaft and having one end slidably supported with relation thereto, an operative connection be- 35 tween the driving pulley and the counter shaft, a drum mounted on the counter shaft, an auxiliary pulley keyed to the counter shaft at the slidable end and in alignment with the fly wheel, means for shifting said 40 slidable end to bring the auxiliary pulley into and out of engagement with the fly wheel, and a brake lever pivoted to the frame at a point in advance of the auxiliary pulley and adapted to engage the same. 50

In witness whereof I have hereunto set my hand.

AIMÉ BOULANGER.
